UNITED STATES PATENT OFFICE.

JAMES REAGAN, OF PHILADELPHIA, PENNSYLVANIA.

GRATE.

SPECIFICATION forming part of Letters Patent No. 635,607, dated October 31, 1899.

Application filed January 6, 1899. Serial No. 701,333. (No model.)

To all whom it may concern:

Be it known that I, JAMES REAGAN, a citizen of the United States, residing in the city and county of Philadelphia and State of Pennsylvania, have invented a new and useful Improvement in Grates, of which the following is a specification.

My invention relates to grates of the rocking-bar type, its principal object being to keep the bed of fuel which is carried by the grate free from the clinker and ashes that would retard the admission of air to the combustion-chamber and to render the operation of the choppers, which are borne by the rocking bars, easy of accomplishment.

The aforesaid objects are attained by the use of floating choppers of peculiar construction in connection with coacting elements, as will hereinafter appear.

20 The exact nature of the invention will be understood by a perusal of the following detailed description in connection with the several appended claims.

Figure 1 is a vertical longitudinal section of 25 a grate embodying my invention. Fig. 2 is a cross-sectional view on the line A B of Fig. 1. Fig. 3 represents a chopper detached from its bar. Figs. 4 and 5 show spanners through the medium of which the bars are rocked. Fig. 30 6 is a view of a portion of one of the rocking bars. Fig. 7 is a cross-sectional view of a fragment of a bar and chopper.

A is the entire frame of the grate, having within it two rows of chopper-bars A' A'', 35 which are separated by a stationary cross-bar B, having cutting edges b b'.

C C' are the end bars of the grate-frame, which are provided with cutting edges c c'.

D are the choppers, each of which consists 40 of an elongated body of suitable material, provided with downwardly-flared clearance-openings d for the passage of ashes, lateral clinker-crushing teeth d', and end cutters d'', each provided with a downwardly-projecting 45 cutting edge d'', which in the operation of the choppers cooperates with one of the upwardly-projecting cutting edges b b' c c' upon the middle and end cross-bars. By the use of this construction I am enabled to readily 50 crush, cut, or dislodge all clinkers which are caught between the choppers and the middle,

end, and intermediate bars of the grate-frame and to cut away and remove all ashes and masses of clinkers which form in the lower layers of the incandescent fuel. Each chopper has a recess d', which is angular in cross-section and corresponds in shape to the angular portions e of the rocking bars K. This recess is somewhat larger than the angular portion of the bar, so as to admit of considerable movement of the chopper on the bar and to provide for the floating effect of the chopper, to which I have already referred. This construction is especially useful in connection with vehicles, such as locomotive-engines, whose movements impart a slight vibratory action to the floating bars and cause an automatic sifting out of the ashes as the vehicle pursues its course. It is also useful in the particular that it admits of universal 70 movements of the choppers when they are shaken in the usual manner and a consequent thorough agitation of the fuel in all directions and also because it allows large pieces of clinker to pass between the choppers, which 75 may readily move in opposite directions to afford a large space between them for that purpose.

A still further advantage of the universal and free mounting of the choppers is that 80 when actuated they do not have to be moved together as a dead weight, for as they will necessarily stand in various slightly-different positions motion will be successively imparted to them as the operating-lever is actuated. 85 This fact renders the shaking of the grate comparatively easy of accomplishment.

Each grate-bar E is provided with cylindrical portions e', whose diameters are smaller than the entrance d'' of any of the recesses 90 d' of the choppers, so that the choppers may be placed upon the rocking bars and slipped into engagement with the angular portions e thereof, which lock them in radial position.

If F' are spanners of an ordinary type, the 95 long ones, F, being connected with the usual shaking-lever I and the short ones, F', being united to the long ones by links N.

All of the spanners are provided with recesses f f', which adapt the spanners to be 100 locked upon the angular portions of the grate-bars in the same manner that the choppers

are secured thereon, with the distinction, however, that there is little or no play or looseness upon the bars, as in the case of the choppers.

5 K are stationary bars alternating with the choppers.

The operation of the grate will be apparent from the foregoing description and need not be further described.

Having thus fully described my invention,
10 what I claim is—

1. The combination of a series of grate-bars, a set of floating choppers mounted on each of the said bars, and means connected with the grate-bars for actuating said choppers, substantially as described.

2. The combination of a series of rotatory grate-bars, a set of floating choppers mounted on each of said bars and means connected with the grate-bars for actuating said choppers, substantially as described.

25 3. The combination of a series of grate-bars, a set of spaced floating choppers mounted on each of the said bars, stationary bars situated between the choppers and means connected with the grate-bars for oscillating said choppers, substantially as described.

4. The combination of a series of angular grate-bars each provided at intervals with reduced or cylindrical portions, and a series of 30 floating choppers mounted on said bars each chopper having an open socket conforming to the shape of the bars, the entrance to said socket being wider than the diameters of the reduced or cylindrical portions, and narrower

than a diagonal of the bars, substantially as described.

5. The combination of a series of angular grate-bars each provided at intervals with reduced or cylindrical portions, and a series of floating choppers and spanners mounted on said bars each having an open socket conforming to the shape of the bars, the entrance to said socket being wider than the diameters of the reduced or cylindrical portions, and narrower than a diagonal of the bars, substantially as described.

6. The combination of a series of grate-bars, and a set of floating choppers mounted on each of said bars, substantially as described.

7. A chopper for grates consisting of an elongated body having at its ends downwardly-projecting cutting edges d^3 , in combination with a grate-frame having upwardly-projecting cutting edges arranged to coact with the downwardly-projecting cutting edges of the chopper, substantially as described.

8. A chopper for grates consisting of an elongated body having at its ends downwardly-projecting cutting edges d^3 , and interior clearance-spaces, d , in combination with a grate-frame provided with upwardly-projecting cutting edges c^3 , substantially as described.
